UNITED STATES PATENT OFFICE.

PETER DEISSLER, OF PHILADELPHIA, PENNSYLVANIA.

DESIGN FOR A PRISM-PLATE.

SPECIFICATION forming part of Design No. 32,802, dated June 5, 1900.

Application filed April 12, 1900. Serial No. 12,641. Term of patent 14 years.

To all whom it may concern:

Be it known that I, PETER DEISSLER, a citizen of the United States, residing at Philadelphia, in the county of Philadelphia and State of Pennsylvania, have invented and produced a new and original Design for Prism-Plates, of which the following is a specification, reference being had to the accompanying drawings, forming part thereof.

10 Figure 1 is a plan view of a prism-plate, showing my new design. Fig. 2 is a side view thereof along the line 2 2 of Fig. 1. Fig. 3 is a side view thereof along the line 3 3 of Fig. 1.

15 As shown in the drawings, the principal

feature of my design consists of the right rectangular pyramidal projections A, having the convex cylindrical faces *a* disposed or arranged upon one side of the plate, while the opposite side of the plate comprises a series 20 of parallel prismatic ribs B.

Having described my invention, what I claim as new, and desire to secure by Letters Patent, is—

The design for a prism-plate as shown and 25 described.

PETER DEISSLER.

Witnesses:

JOHN THIEL,
P. H. GRANGER.
